UNITED STATES PATENT OFFICE

164,989

MOTOR SCOOTER FRAME

Carlo Guzzi, Mandello Lario (Como), Italy, assignor to Moto Guzzi S. p. A., Genoa, Italy

Application November 8, 1950, Serial No. 12,909
In Italy July 20, 1950

Term of patent 7 years

(Cl. D90—8)

To all whom it may concern:

Be it known that I, Carlo Guzzi, citizen of Italy residing at Mandello Lario (Como), Italy, have invented a new, original, and ornamental Design for a Motor Scooter Frame, of which the following is a specification, reference being had to the accompanying drawing, forming part thereof:

Fig. 1 is a perspective view taken from the right hand side and slightly to the front of a motor scooter frame showing my new design.

Fig. 2 is a perspective view taken from the left hand side and slightly to the front of the motor scooter frame shown in Fig. 1.

I claim:

The ornamental design for a motor scooter frame, as shown.

CARLO GUZZI.
